UNITED STATES PATENT OFFICE

JOHN M. SHIELDS, OF CHICAGO, ILLINOIS, ASSIGNOR TO F. H. NOBLE & CO., OF CHICAGO, ILLINOIS, A CORPORATION OF ILLINOIS

DESIGN FOR A COVERING FOR JEWELRY BOXES AND THE LIKE

Application filed August 10, 1929. Serial No. 32,376. Term of patent 7 years.

To all whom it may concern:

Be it known that I, JOHN M. SHIELDS, a citizen of the United States, residing at Chicago, in the county of Cook, State of Illinois, have invented a new, original, and ornamental Design for Covering for Jewelry Boxes and the like, of which the following is a specification, reference being had to the accompanying drawing, forming a part hereof, wherein the figure is a plan view of the covering for jewelry boxes and the like constituting my new design.

The vertical lining on the drawing represents light and dark shades of the same color, while the horizontal lining represents contrasting color to the vertical lining, the shading of the stripes indicating graduating density of the same shade.

I claim:

The ornamental design for covering for jewelry boxes and the like as shown and described.

JOHN M. SHIELDS.
